UNITED STATES PATENT OFFICE.

LEMMA J. ROOT, OF SEATTLE, WASHINGTON.

SPRING.

Application filed September 17, 1923. Serial No. 663,091.

The invention is a leaf spring having a raised portion at the center to hold the leaves longitudinally and laterally in position and grooves in the leaves through which they may be readily lubricated and also a horizontal leaf for catching the rebound and assisting a light load to ride as easy as a heavy load.

The object of the invention is to provide a spring with grooves whereby the spring may be readily lubricated.

Another object of the invention is to provide a means whereby a leaf spring may be held in position without the use of a bolt or a welded center as is now used.

And a further object of the invention is to provide a means for catching the rebound of a spring and assisting the vehicle in riding with a light load so that it will ride as easy as a heavy one.

With these and other ends in view the invention embodies a leaf spring in which the leaves are provided with grooves and oil holes and an extra leaf of different curvature.

Other features and advantages of the invention will be seen from the following description taken in connection with the drawings, wherein:—

Figure 1 is a side elevation showing a spring in the free position.

Figure 2 is a longitudinal section through the central portion of the spring.

Figure 3 is a cross section through the center of the spring.

Figure 4 is a detail showing the shape of the grooves.

Figure 5 is a view showing the position of one end of the spring under load.

Figure 6 is a view showing the position of one end of the spring under a heavy load or shock.

In the drawings I have shown my spring as it would be constructed wherein numeral 1 indicates the upper leaf, numerals 2 and 3 the intermediate leaves, numeral 4 the extra straight leaf, and numeral 5 the short leaf at the center. The outer end of the leaf 1 may be attached by links 6 to a frame 7 or to any suitable device and when in the free position it will be in the position shown in full lines. The outer end of the leaf 4 may be

attached to the outer end of the leaf 1 by a link 8 as shown in dotted lines in Figure 1, and when in position it will draw the outer end of the leaf 1 downward to about the position shown in dotted lines in Figure 1. It will be seen that this will always have a tendency to hold the ends of the spring downward and when the spring is released quickly as in the case of a rebound the leaf 4 will tend to hold the spring downward and thereby prevent its returning to the normal position with a quick jerky movement. It will also be seen that the leaf 4 will assist a light load in a downward movement until the spring arrives at a free position of leaf 4 and from this position downward it will aid the spring in carrying the load as the tendency of the outer end of leaf 4 will be to move upward. It will therefore, be possible to obtain the ease while riding with a light load that is obtained with a heavy load.

The leaves are provided with longitudinal grooves 10 in their centers and at the centers of these grooves are conical shaped sections 11 which have openings 12 in their vertexes. The sections 11 hold the leaves longitudinally and laterally so that it will not be necessary to use a bolt in the center of the spring as straps around the leaves holding the spring to a vehicle will also hold them in position from swinging. It will also be seen that oil may be placed in the opening 12 to lubricate the leaves through the grooves 10. This will make it possible to attain perfect lubrication between the leaves of the spring at all times and with very little trouble. It will also be seen that oil may be placed in the openings 12 with an oil can, grease cup, or any suitable means.

It is understood that although I have shown my device embodied in a semi-elliptical spring it may be embodied in a spring of any suitable type or design.

Having thus fully described the invention, what I claim as new and desire to secure by Letters Patent, is:—

In a spring, a plurality of curved leaves, means at the ends of the uppermost leaf for attaching it to an object to be supported, each of the said successive leaves being somewhat

shorter than its predecessor, another leaf at the bottom of the shortest leaf of the said spring of substantially the same length as the uppermost or longest leaf of the said spring, 5 and suitable links for pivotally connecting the ends of the said latter leaf to the ends of the said uppermost leaf, the said latter leaf

being substantially straight in its free position and when attached to the said spring its ends will be curved upward by the action of 10 the said spring and the ends of the said spring will be slightly curved downward by the action of the said latter leaf.
